UNITED STATES PATENT OFFICE.

HARVEY ABRAMES, OF NORFOLK, VIRGINIA.

HYDRAULIC PILING.

Application filed October 20, 1921. Serial No. 509,058.

To all whom it may concern:

Be it known that I, HARVEY ABRAMES, a citizen of the United States, residing at Norfolk, in the county of Norfolk and State of Virginia, have invented certain new and useful Improvements in Hydraulic Piling, of which the following is a specification.

My invention relates to hydraulic piling.

The object of the invention is to provide means for efficiently sinking cement or concrete piles by the aid of jets of water, for foundations of buildings, bridges and the like.

Further objects and advantages will be more fully described herein and specifically pointed out in the claim hereunto annexed recourse being had to the accompanying drawing forming a part of this specification in which:

20 Figure 1 is a sectional view of the hydraulic water jet apparatus.

Figure 2 is a sectional elevation of a concrete or cement pile with my device in place therein.

25 Figure 3 is a sectional plan on the line 1-2 in Figure 1, and

Figure 4 is an elevation of one end of the connecting link with a bifurcated extremity.

In the drawing like reference numerals 30 indicate similar parts in all the several views:

1 represents the tapering cement or reinforced concrete pile which is provided with a bore or hole 2 vertically throughout its length both for lightness, strength and for the hereinafter described hydraulic cylinder 35 to be placed therein and afterwards withdrawn at will.

In order to sink the pile by displacing the sand or earth by jets of water at high pressure, the hydraulic cylinder 3, is lifted by a derrick or otherwise placed in the hole 2 of the pile and allowed to discharge water at the lower end of the pile which washes 45 away the sand or soil and allows the pile to settle to its place, after which the flow of water is discontinued and the cylinder withdrawn for a subsequent operation.

The hydraulic cylinder consists of a shell 50 3 terminating in a point 3^a, at its lower end, and contains the mechanism to be hereinafter described. 4 is a sleeve having a centrally located screw thread 5 and having a portion of the same, as at 6, Figure 1, 55 within the cylinder or casing 3.

The upper part 4 of the sleeve is adapted

to receive a hose 6^a by which water is conveyed to the cylinder 3.

The lower part of the sleeve 4, as at 6, is provided with a bevelled edge to act as a seat 7 for the valve 8.

9 is a cross bar provided with flanges 10 and holding bolts 11, secured to the inner part of the cylinder 3, and is furnished with an orifice or bore for the slidable passage 65 of the valve stem 12 and acts as a guide and support therefor.

Between the valve 8 and the cross bar 9 there is placed a coiled or spiral spring 13 which exerts a pressure against the valve 8 70 to keep it fast upon its seat until overcome by the superior pressure of the water and therefore closes it when the water is shut off.

Connected to the valve stem 12, by the 75 yoke 14, is a link 15 which is in turn connected by another yoke 16, to the ends of the levers 17 which are normally at right angles to the axis of the cylinder 3, and are pivoted on the rods 19, as in Figures 1 80 and 3.

The levers are also bent upwards nearly at right angles but curved, as at 18, Figure 1.

All the joints at the yokes are suitably ful- 85 crumed on pins in the usual manner.

In order that my invention may be effective, the point of the jetting device should extend slightly below the point of the concrete pile, 1, and water should flow there- 90 through. This object is accomplished by inserting the said device in the pile, whereupon water immediately starts to flow through the point due to the fact that the levers 18, are depressed by engagement with 95 the bore of the pile and thereby open the valve. However, when the point is forced below the foot of the pile, the spring, 13, closes the valve, thus cutting off the water supply and forces the arms, 18, outwardly. 100 This stopping of the water flow indicates to the operator that the point has passed below the foot of the pile. Thereupon, the device is raised slightly to cause the upper portions of the arms to re-engage the walls of the 105 bore of the pile and re-open the valve, where it is held in an operative position.

The bottom of the slots 20 are made sloping so as to direct the water downwards as 110 are also the jet orifices 22.

23 are horizontal jets, (which may be ar- ranged so as to give the water a spiral or

tangential flow), and 24 are vertical orifices for the water and there may be any number desired also placed at any angle.

25 are suitable wire ropes by which the cylinder 3 may be lifted by a crane or other means, into the bore of the pile 1.

I claim:—

In a device of the class described, the combination with a pile having a longitudinal bore therethrough, of a cylinder in said bore having a closed point thereon pro-

vided with jet orifices, a valve in said cylinder, means extending through the periphery of said cylinder and controlled by said bore for opening said valve, a spring for closing said valve, and means for suspending said cylinder in said bore. ¹⁵

HARVEY ABRAMES.
